UNITED STATES PATENT OFFICE.

LOUIS GODDU, OF WINCHESTER, ASSIGNOR TO JAMES W. BROOKS, PRINCIPAL TRUSTEE, OF CAMBRIDGE, AND FRANK F. STANLEY, ASSOCIATE TRUSTEE, OF SWAMPSCOTT, MASSACHUSETTS.

METHOD OF BURNING CRUDE PETROLEUM.

SPECIFICATION forming part of Letters Patent No. 443,660, dated December 30, 1890.

Application filed November 9, 1889. Serial No. 329,769. (No model.)

To all whom it may concern:

Be it known that I, LOUIS GODDU, of Winchester, county of Middlesex, State of Massachusetts, have invented an Improvement in 5 Methods of Burning Crude Petroleum, of which the following description, in connection with the accompanying drawing, is a specification, like letters on the drawing representing like parts.

10 This invention has for its object to provide a novel method for the consumption of crude petroleum.

Prior to my invention I am aware that attempts have been made to employ crude petroleum as a fuel for heating purposes; but prior to my invention this has not been successfully done, so far as I am aware, because the heavier hydrocarbons, when subjected to heat, are deposited in the burner or apparatus employed, such deposit accumulating rapidly and choking up the burner or apparatus, the said material deposited as described being further deleterious because it forms a non-heat-conducting coating or lining within 20 the burner.

25 By repeated experiments I have ascertained that crude petroleum may be successfully burned by heating the burner on its under side by the flame arising from the combustion of the crude petroleum in the burner, whereby the crude oil is heated intensely and the heavier hydrocarbons are thereby disintegrated to such extent as to be readily consumed.

30 My invention therefore consists in that improvement which consists in igniting crude petroleum in a shallow trough or burner and heating the burner on its under side by the flame generated by the combustion of the crude petroleum in the burner, substantially 35 as will be described.

The drawing represents in section and elevation a sufficient portion of a fire-tube boiler provided with a petroleum-burner to enable 40 my invention to be understood.

45 The boiler A, herein shown as an upright fire-tube boiler, has located in its fire-box A' a burner for the consumption of crude oils, which is substantially such as shown and de-

scribed in another application, Serial No. 50 322,662, filed by me September 2, 1889.

The burner referred to is composed of an annular shallow trough a , having secured to or forming part of it an upwardly and preferably outwardly expanded or extended side 55 wall a' . The side wall a' is provided on its outer side with legs or studs a^2 , which project down at intervals, so as to leave an opening a^3 between every two adjacent legs for the passage of air. Each depending leg a^2 , as 60 herein shown, is provided with a slot into which is fitted the upper end of a concave plate or wall a^4 , constituting a deflector, the said legs being secured to the said plate or wall in any desired or suitable manner. The 65 deflecting-wall a^4 is shown in Fig. 1 as circular in form to conform to the shape of the shallow trough, and the said deflecting-wall forms with the outer upturned side of the said trough a passage a^6 , through which the 70 flame from the burning oil is directed down under and in contact with the bottom of the shallow trough.

The deflecting-wall a^4 in the present instance is cored annularly near its upper end 75 above the shallow trough to form a circumferential passage a^6 , having its inlet mouth or port connected to a steam-inlet pipe a^9 , provided with a cock or valve a^{10} , the outlet end or mouth of the passage a^6 communicating 80 with the radial passage a^7 , formed in the deflecting-wall. The passage a^7 extends down to the bottom of the deflecting-wall a^4 and communicates with the interior of the burner through a port, which is controlled, as herein 85 shown, by a plug-valve a^8 . The steam-inlet pipe a^9 in practice is connected to the steam-dome of the boiler.

The passage a^7 at its upper end, preferably at the junction of the said passage with the 90 circumferential passage a^6 , may be provided with an outlet-port a^{12} , located above the shallow trough a , and adapted to admit steam into the space between the side walls a' and deflecting-wall a^4 above the said trough, the 95 said outlet-port being controlled, as herein shown, by a plug-valve b , extended through a hollow arm b' of the deflecting-wall a^4 , the

said arm being extended through the side of the boiler, as herein shown, and provided with a suitable stuffing-box b^2 of any usual construction.

5 The crude petroleum-oil is supplied to the burner or shallow trough through a pipe b^3 , extended through the boiler-shell and connected to a valve-casing b^4 , having its inlet-port connected by a pipe b^5 to a supply-tank b^6 , the pipe b^5 being supplied with a suitable cock or valve b^7 . The valve-casing b^4 is provided with a suitable valve, which is substantially such as shown and described in the said application, the said valve being connected by lever b^8 and rod b^9 to the lever b^{10} , secured to or forming part of a regulator b^{12} , communicating with the steam-space of the boiler. The valve of the casing b^4 is also connected by levers b^{13} and rod b^{14} to a float b^{15} , 20 contained within a vessel or receptacle b^{16} , which is connected by a pipe b^{17} to the lower portion of the burner.

15 The boiler will be provided with the usual dampers, (not shown,) by which air may be admitted to the fire-box to support combustion.

25 In operation the oil is admitted into the shallow trough a and is ignited, and the air in the fire-box passes through the spaces a^3 and down through the passage a^5 , carrying with it the flame arising from the burning oil,

the said flame then passing upward through the burner, so that the said burner is intensely heated on its underside, and the heavier particles or hydrocarbons of the crude petroleum are in this manner disintegrated to such extent as to be readily consumed. By causing the flame arising from the burning oil to pass through the burner, as described, it will be seen that the oil in the burner is subjected on all sides to an intense heat. In other words, the said oil is practically surrounded or enveloped by flame, whereby the disintegration of the heavier hydrocarbons is effected.

35 I claim—

40 The herein-described method of burning crude petroleum-oil, which consists in igniting the crude petroleum in a shallow trough or burner and heating the burner on its under side by the flame generated by the combustion of the crude petroleum in the burner, whereby the heavier hydrocarbons are disintegrated and consumed, substantially as described.

45 In testimony whereof I have signed my name to this specification in the presence of two 50 subscribing witnesses.

LOUIS GODDU.
